UNITED STATES PATENT OFFICE

ELWOOD T. LARKIN, OF BUFFALO, NEW YORK, ASSIGNOR TO CHARLES A. CRIQUI, OF BUFFALO, NEW YORK

DRIP PAN FOR CARBURETORS

Application filed November 22, 1929. Serial No. 409,119.

This invention relates to carburetors provided with pans for collecting the drip or leakage of liquid fuel from the carburetors.

All carburetors used to vaporize gasoline or other liquid fuel for use in internal combustion engines have a tendency to leak slightly, and in the event of the engine rotating in the reverse direction when stopping, fuel is sometimes blown out at the carburetor air inlet passage. Both of these causes provide a bad fire hazard and possibility of engine room explosions, if the engine is installed in a confined space with inadequate ventilation as in marine installations.

Attempts have heretofore been made to remedy this fire and explosion hazard by installing an open pan under the carburetor, which pan will collect this seepage. A pan of this kind, however, has the disadvantage of exposing a relatively large surface of the fuel to the atmosphere, which causes the gasoline to become readily evaporated so that the fire hazard and possibility of explosions are not materially reduced by the provision of a pan of this kind.

The objects of this invention are to provide a drip pan for carburetors which is formed so that the upper edges of the pan conform closely to the contour of the carburetor, these edges being formed so that fuel flowing downwardly on the walls of the carburetor will enter the pan; also to provide a drip pan of this kind in which the carburetor itself acts as a cover or closure for the pan so that the evaporation of fuel from the pan is materially retarded; also to provide a construction of this kind by means of which fuel collected in the pan can be quickly disposed of; also to provide a carburetor with means permitting excess gasoline from the suction or mixing passage of the carburetor to be discharged into the drip pan, and thus prevent the blowing of this excess fuel through the air opening of the carburetor, in case the engine turns in the reverse direction on stopping; also to improve the construction of devices of this kind in other respects hereinafter specified.

In the accompanying drawings:

Fig. 1 is a longitudinal sectional elevation

of a carburetor and a drip pan embodying this invention;

Fig. 2 is a transverse sectional elevation thereof on line 2—2, of Fig. 1;

Fig. 3 is a fragmentary transverse sectional elevation showing a slightly modified arrangement for returning fuel from the drip pan to the carburetor.

The carburetor shown in the accompanying drawings is merely illustrative of how my invention may be applied to a carburetor and it is not intended to restrict this invention to use in connection with the particular carburetor shown, since it will be obvious that the invention may be employed in connection with carburetors of other constructions.

In the particular carburetor shown, A represents the usual float chamber having a float a therein which controls a fuel valve b in the usual manner to maintain a substantially uniform quantity of fuel within the flat chamber A. B represents the fuel supply pipe. C is the air intake passage of the carburetor, the air receiving end of which is supplied with a combined air cleaner and flame arrester D which may be of any suitable or well known construction. This air intake passage C terminates in a discharge passage E controlled by a throttle valve e and which is connected in the usual manner to the intake pipe or manifold of an engine, (not shown). The fuel in liquid form is carried to the lower portion of the discharge passage E by means of a duct or tube F, which is connected near its lower end with the fuel supply in the float chamber by means of an aperture or passage f.

In order to catch any fuel which might escape from the carburetor or from any of the connections leading to the carburetor, a drip pan G is provided which is so formed as to enclose the lower portion of the carburetor. This drip pan includes a body portion 10, which is formed to slope from the outer portions thereof downwardly to a sump or depressed part 11. The upper edges of the body portion 10 terminate in flanges 12 which extend inwardly and downwardly, the inner edges 13 of the flanges sloping downwardly and are preferably arranged to either

contact with or approach closely to the outer wall of the carburetor.

The drip pan D may be secured to the carburetor in any suitable or desired manner, and in the construction shown for this purpose, attaching lugs 15 are provided on the drip pan, for example, on the inwardly extending flanges 12 thereof, and are secured to the walls of the carburetor in any suitable manner, for example, by means of screws 16. By means of this connection with the carburetor, a drip pan can be easily and quickly removed, when desired, but other means for securing the drip pan to the carburetor may be employed, if desired.

As a result of the construction described, all gasoline or other fuel escaping from the carburetor by leakage will be collected in the drip pan D and drained to the sump 11 thereof. Any fuel which runs down along the side walls of the carburetor and contacts with the flanges 12 will be guided into the drip pan because of the downward and inward inclination of the flanges 12, and the end portion 13 thereof. Gasoline and most other motor fuels will readily pass between the inner edge 13 and the wall of the carburetor, even if these two parts are in contact, since the fuel will readily pass through small crevices or gaps. Most of the leaks occur in such a manner that the fuel will tend to flow along the walls of the carburetor, and consequently a pan of greater size relatively to the size of the carburetor than that shown is seldom necessary, but, if desired, the pan can be enlarged by increasing the width of the flange 12, for the purpose of catching drip from connections with the carburetor which may not follow the carburetor walls.

The sump 11 in the drip pan is preferably covered by means of a screen or strainer 17, which strains the fuel entering the sump and excludes foreign matter. In order to dispose of the fuel entering the sump, a suction pipe or duct connecting with the suction passage E of the carburetor or the intake manifold or pipe of the engine is provided. In the particular construction shown in Figs. 1 and 2, a pipe H is provided for this purpose which extends into close proximity with the bottom of the sump 11. The upper end of this tube terminates near the discharge end of the fuel supply pipe or duct F, and the upper end 20 of this tube is preferably tapered or restricted so as to limit the quantity of air or fuel admitted through this passage by the suction produced in the passage E of the carburetor. This tube will, consequently, draw any fuel collecting in the sump upwardly into the suction passage E of the carburetor where the fuel will be vaporized by contact with the air rushing through this tube.

In the modified construction shown in Fig. 3, a suction pipe H¹ is provided, which extends from the sump 11 in the drip pan G

along the outer side wall of the carburetor and extends at its upper end through a hole or opening in the carburetor, so that this end of the tube is subjected to the suction of the intake passage E, and also draws fuel from the sump and discharges it to the intake passage E. Any other means for drawing fuel from the sump and discharging it to the engine intake may be provided.

In carburetors as now made, it frequently happens that an excess of liquid fuel is fed to the suction passage E and collects in the bottom of the air intake chamber of the carburetor. When the engine is stopped, it frequently happens that, just before coming to a stop, the engine will be given an impulse in the reverse direction, causing a mixture of air and fuel to be blown backwardly through the carburetor, and this frequently results in the fuel in the air chamber in the carburetor being blown out through the air intake. This, of course, forms a dangerous fire hazard, and in order to prevent this from occurring I provide means for draining any fuel that may have collected in the air chamber into the drip pan G. This may be done by any suitable or desired means, for example, by providing a drain plug K, one end of which is screwed into a threaded hole in the lower wall of the air chamber or passage of the carburetor, and which is filled with metal wool 22 or other means for arresting flame. The lower end of the plug being provided with an opening 23, through which the fuel discharges into the drip pan after it has passed through the metal wool or other flame retarding means. By this arrangement, any fuel in the bottom of the air intake passage will be quickly and efficiently drained into the sump 11.

At certain times, it may be possible that so much fuel drains into the drip pan D as to tend to overflow this drip pan before the fuel can be withdrawn through the restricted discharge pipe H, and in order to prevent the drip pan from overflowing, a discharge pipe 25 may be provided, which connects with the drip pan at an elevation considerably above the sump 11 and above the strainer 17. This overflow pipe 25 may lead to any convenient place or receptacle (not shown), such, for example, as a storage tank or vessel to receive this excess fuel, or, in the case of marine installations, this pipe may lead overboard.

The drip pan shown has the advantages that in the first place, it is attached directly to the carburetor itself, so that it is always in position to receive any drip or seepage from the carburetor, even in extreme cases of rolling of a boat, or in other unusual positions of the engine, and this arrangement, therefore, also makes it possible to provide a drip pan of the minimum size. Furthermore, by attaching the drip pan directly to

the carburetor, the bottom wall of the carburetor forms a cover or closure for the top of the drip pan, so that evaporation is materially reduced. By providing a suction connection with the drip pan for withdrawing fuel from the drip pan, there will be a continual inward flow of air at the points of contact between the inner edges of the flanges 12 of the drip pan and the wall of the carburetor, which in-flow of air into the drip pan will prevent any evaporated fuel from passing out of the drip pan while the engine is running. By the use of the drip pan in connection with the overflow arrangement of the air intake pipe of the carburetor, this air intake passage is kept at all times free from liquid fuel, so that in case of rotating or partial rotation of the engine in a reverse direction no liquid fuel will be blown through the air intake opening of the carburetor. The flanges 12 of the drip pan, in addition to the functions described, also act as splash guards when the engine and carburetor are subjected to unusual motions or rolling.

25 Claims:

1. The combination of a carburetor, a drip pan therefor arranged entirely exterior of the carburetor, means connecting said drip pan and said carburetor for securing said drip pan on said carburetor, the lower wall of the carburetor acting as a cover for the drip pan to prevent rapid evaporation of fuel collecting in the drip pan.

2. A carburetor drip pan in accordance with claim 1 characterized in that the upper edges of the drip pan are provided with flanges extending inwardly into close proximity to the wall of the carburetor.

3. A carburetor drip pan in accordance with claim 1 characterized in that the upper edges of the drip pan have flanges extending inwardly and downwardly into close proximity to the wall of the carburetor to guide fuel contacting with these flanges into said drip pan.

4. A drip pan for a carburetor, including a body portion terminating in a sump, inwardly extending flanges at the upper edge of said body portion extending toward the walls of said carburetor, said flanges sloping downwardly toward the carburetor wall to guide liquid fuel contacting with the flanges into said drip pan, means secured to said drip pan for releasably mounting said drip pan on said carburetor, whereby the lower portion of the carburetor forms a cover for the drip pan, and means for withdrawing fuel from said sump.

5. The combination of a carburetor having a suction passage, a drip pan therefor, having a sump, means for securing said drip pan to the carburetor, a duct extending from said suction passage to said sump for drawing fuel from said sump to said carburetor, and an overflow pipe connected to said drip pan

at an elevation above said sump to remove fuel from said drip pan when an excessive quantity of fuel enters said drip pan.

6. The combination of a carburetor having a suction passage and an air intake passage, a drip pan therefor, a tube connecting said suction passage with said drip pan to remove fuel from said drip pan and to discharge the same to said suction passage, and means for draining liquid fuel collecting in said air intake passage into said drip pan.

7. The combination of a carburetor having a suction passage and an air intake passage, a drip pan therefor, a tube connecting said suction passage with said drip pan to remove fuel from said drip pan and to discharge the same to said suction passage, a drain hole in the lower end of said air intake passage through which liquid fuel collecting in said air intake passage may pass into said drip pan, and flame arresting means of finely divided metal through which liquid fuel must pass from said hole into said drip pan.

8. The combination of a carburetor having a suction passage and an air intake passage, a drip pan therefor, a tube connecting said suction passage with said drip pan to remove fuel from said drip pan and to discharge the same to said suction passage, and a drain plug arranged in the lower wall of said air intake passage and having a passage therethrough through which liquid fuel may pass from the lower end of said air intake passage to said drip pan, and flame arresting means arranged in said plug and through which the liquid fuel must pass.

9. A drip pan for a carburetor formed to be attached to the carburetor below the same to receive any liquid dripping from the carburetor, the carburetor cooperating with the drip pan to form a closure therefor to prevent rapid evaporation of fuel in the drip pan.

10. A drip pan for a carburetor formed to be attached to the carburetor below the same to receive any liquid dripping from the carburetor, the carburetor cooperating with the drip pan to form a closure therefor to prevent rapid evaporation of fuel in the drip pan, means for withdrawing fuel from said drip pan into said carburetor, and means for draining into said drip pan fuel collecting in the air intake passage of the carburetor.
